UNITED STATES PATENT OFFICE.

ROBERT M. CATHCART, OF BALLSTON, VIRGINIA.

TRIMMER FOR PHOTOGRAPHIC PRINTS.

1,267,055.

Specification of Letters Patent. Patented May 21, 1918.

Application filed May 22, 1917. Serial No. 170,810.

To all whom it may concern:

Be it known that I, ROBERT M. CATHCART, a citizen of the United States, residing at Ballston, in the county of Alexandria and State of Virginia, have invented certain new and useful Improvements in Trimmers for Photographic Prints, of which the following is a specification.

This invention relates to an improved 10 trimmer for photographic prints and has as its primary object to provide a device of this character which will be illuminated in such manner that the edges of the picture may, without regard as to whether the picture is face up or down, be easily discerned and the print thus accurately trimmed with the proper margins.

The invention has as a further object to provide a trimmer having a transparent cutting table illuminated from beneath so that 20 the edges of a picture placed on the table to be cut may be easily seen.

The invention has as a further and equally 25 important object to provide a trimmer wherein the light will be directed against the outer side of the fixed blade of the cutting knife so that when a print is projected over the said blade to be cut the light will strike the print making it easily possible 30 to quickly perceive the adjacent edge of the picture and accordingly position the picture for trimming with a proper margin.

A still further object of the invention is to provide a trimmer having a reflector for 35 directing the light up through the cutting table and also a reflector arranged to direct the light against the outer side of the fixed blade of the trimmer.

And the invention has as a still further 40 object to provide a construction wherein, when a picture having a light background is to be trimmed, the light may, when desired, be cut off immediately at the inner side of the fixed blade of the cutting knife for 45 overcoming any tendency toward fogging of the edges of the picture.

Other and incidental objects will appear 50 as the description proceeds and in the drawings wherein I have illustrated the preferred embodiment of the invention and wherein similar reference characters designate corresponding parts throughout the several views:

Figure 1 is a perspective view of my improved trimmer,

Fig. 2 is a transverse sectional view more particularly showing the mounting of the lamp employed.

Fig. 3 is a longitudinal sectional view illustrating the construction of the body of 60 the device and the mounting of the transparent cutting table, and

Fig. 4 is a front elevation illustrating the mounting of the pivoted cutting blade.

In carrying out the invention my improved trimmer is formed with a preferably 65 rectangular body having parallel side walls 10 joined by a top wall 11. The body may, of course, be varied in dimensions as occasion may demand and is preferably formed 70 from a single piece of suitable sheet metal. At their lower edges the side walls of the body are formed with inwardly directed lateral flanges 12 extending throughout the entire length of the said walls and secured 75 to the said flanges are a plurality of knobs 13 of rubber or other soft material upon which the body is supported.

For a portion of its length the top wall 80 of the body is freed from the side walls thereof and is inclined downwardly and forwardly between the said side walls to provide a reflector 14. This reflector rests at its lower extremity upon the flanges 12 and from the said reflector the material of the 85 top wall is extended along the said flanges to provide the bottom wall 15 of a lamp chamber 16. It is now to be noted that the side walls 10 of the body are, at their forward extremities, formed with reduced extensions 17 having downwardly inclined upper edges and upwardly curved lower edges, the flanges 12 extending along the lower edges of the said extensions and curving therewith. The bottom wall 15 of 90 the lamp chamber is extended along the curved portions of the flanges 12 and is curved upwardly to conform thereto and provide a second reflector 18 concavo-convex in cross section and arranged in advance of 100 the forward end edges of the side walls 10. From the reflector 18 the extended portion of the top wall 11 is then directed between the upper edges of the extensions 17 and conforms to the inclination of the said edges 105 to provide a downwardly inclined shavings board 19 extending above the said reflector. At the forward end edges of the side walls 10 the wall forming the shavings board 19 is then continued upwardly at an angle be- 110

110

ween the said side walls to form an end wall 20 for the lamp chamber 16 and this end wall is rebent upon itself to provide a vertically arranged screen 21 projecting downwardly into the said chamber. Struck from the side walls 10 of the body are a plurality of inwardly directed lugs 22 extending beneath the reflector 14 and secured thereto for connecting the side walls with the reflector and supporting the reflector in position while a plurality of rivets or other suitable fastening devices are employed for connecting the bottom wall 15 and reflector 18 with the flanges 12 of the side walls. This provides a construction whereby the side walls will be effectually braced with respect to each other.

Seating against the front wall 20 of the lamp chamber is the fixed blade 23 of the cutting knife resting at its extremities upon the upper edges of the extensions 17 of the side walls 10 and connected to the end wall 20 by a plurality of rivets or other suitable fastening devices which also extend through the screen 21. The blade will thus be rigidly supported in position and at its upper edge the said blade is preferably of a width substantially equal to that of the margin of an ordinary photographic print with the outer face of the blade slightly inclined to provide a shearing edge at the upper outer corner of the blade. Formed on the forward end edges of the side walls 10 are inwardly directed lugs 24 seating against the inner face of the screen 21 at its extremities and secured to the said screen as well as the end wall 20 of the lamp chamber by one or more of the rivets securing the blade 23. These lugs thus serve to join the side walls 10 of the body with the end wall 20 for bracing the said side walls with respect to each other adjacent the cutting blade 23 and rigidly supporting the said blade. Connected to one of the side walls 10 of the body at one extremity of the fixed blade 23 of the cutting knife is a supporting bracket for the pivoted blade of the said knife. This bracket is formed at its upper extremity with a cam 25 and mounted upon the said bracket is a knife bar 26 swingingly connected to the bracket by a pivot bolt 27 extending through the said bar. The knife bar 26 is, at its inner extremity, provided with a cam 28 to coöperate with the cam 25 of the bracket and at its outer extremity is formed with a suitable handle. Set into the lower edge of the said bar and suitably secured thereto is a pivoted knife blade 29 adapted to coöperate with the fixed blade 23. As particularly shown in Fig. 1 of the drawings, the pivot bolt 27 projects beyond the inner side of the bracket 24 and interposed between the bracket and the nut of the said bolt is a helical spring 30 surrounding the bolt and normally holding the

faces of the cams 25 and 28 of the bracket and knife bar in engagement with each other. Thus, as the knife bar 26 is swung downwardly to move the cutting blade 29 relative to the fixed blade 23, the cams 25 and 28 will coact to increase the tension of the spring 30 and accordingly increase the shearing effect of the blade 29 against the blade 23 as the downward stroke of the blade 29 is completed. Accordingly, the cutting blade 29 will, when swung downwardly, always be urged to coöperate with the blade 23 for easily and quickly trimming the photographic prints.

Closing the upperside of the lamp chamber 16 is a transparent cutting table 31. This table may be formed of glass or other transparent material and is received between the side walls 10 of the body to be supported at its front edge upon the front wall 20 of the lamp chamber and at its rear edge within a transversely extending offset 32 formed in the upper extremity of the reflector 14 with the said table fitting snugly between the said side walls and abutting the cutting blade 23 in a plane with the upper edge thereof. Struck from the side walls 10 are a plurality of inwardly directed lugs 33 engaging beneath the table for supporting the side edges thereof. In thus mounting the table, the said table will, under ordinary circumstances, be held firmly in position while at the same time, the said table may be readily removed when desired. Arranged upon the table to extend parallel with the fixed cutting blade 23 are a plurality of guide lines 34. These guide lines are preferably opaque or nearly so and may be formed of strips of paper pasted to the table. On the other hand, the said guide lines may be painted on the table, if desired, and preferably the said guide lines are each of a width corresponding to that of the ordinary margin of a photographic print while the said guide lines are arranged a similar distance apart. Extending longitudinally of the body 10 and overlying the adjacent margin of the table 31 is a ruler 35 secured at one extremity to the top wall 11 of the body and at its opposite extremity to the fixed blade 23. Formed in the shavings board 19 to extend throughout the major portion of the length thereof is a window opening and set into the said opening is a window 36 of glass or other approved transparent material. The side edges of this window are supported by flanges 37 struck from the shavings board to engage beneath the window and bearing over the ends of the window are spaced lugs 38 also integral with the shavings board. The window will thus be held firmly in position with the said window disposed flush with the upper face of the shavings board.

Mounted within the lamp chamber 16

and connected in any approved manner to one of the side walls 10 of the body is an electric lamp socket 39 of suitable design and detachably mounted within the said 5 socket is a lamp 40. This lamp is preferably of the character shown in Fig. 2 of the drawings to extend throughout the major portion of the width of the lamp chamber and in this connection attention is directed 10 to the fact that the said lamp is mounted adjacent the bottom wall of the chamber opposite the reflector 18 so that an increased portion of the rays from the lamp will strike the said reflector. Moreover it is to 15 be observed that the screen 21 terminates at its lower edge in a plane with the upper edge of the lamp. Mounted within the lamp chamber above the lamp is a rotatable shutter 41 carried by a rod 42 pivoted upon 20 the side walls of the body 10 and projecting laterally with respect to the body at one side thereof to receive a knob 43. This shutter is arranged close to the screen 21 so that when the said shutter is moved to 25 active transverse position, as illustrated in Fig. 3, the adjacent edge of the shutter will closely approach the screen.

Current may be supplied to the lamp 40 from any suitable source and as will now be 30 understood from the preceding description, the rays from the lamp will be deflected by the reflector 14 up through the cutting table 31 while at the same time the reflector 18 will also act to direct the rays from the 35 lamp up through the window 36 against the outer side of the fixed blade 23 of the cutting knife at the shearing edge thereof. Accordingly, a photographic print may be placed upon the cutting table and the edges 40 of the picture readily discerned without regard as to whether the picture is right side up or upside down. Owing to the provision of the guide lines 34, the print may then be easily positioned with an edge of 45 the picture arranged parallel to the cutting blade 23 when the print may be moved forwardly upon the table to project over the said blade. Since the upper edge of the cutting blade 23 is of a width corresponding 50 to the width of the margin to be trimmed upon the picture, the picture is advanced until the adjacent edge thereof passes over the front edge of the cutting table and is rendered opaque by the adjacent edge of 55 the cutting blade when the pivoted blade may be moved downwardly for accurately trimming the print. This provides an arrangement wherein light and shadow are employed for properly positioning the print 60 and owing to the ease with which the shadow of the fixed blade 23 may be determined upon the print when an edge thereof is moved from the transparent cutting table 31 onto the blade, the operation of trimming 65 photographic prints is very much simpli-

fied while at the same time the trimming operation will be more accurate. In any instance where a photographic print having a light background is to be trimmed, the shutter 41 may be employed. This shutter 70 will, when moved to transverse position, cut off the major portion of the light immediately at the inner side of the fixed cutting blade to thus overcome any tendency toward fogging of the edges of the picture. However, it will be noted that the shutter is so arranged that a crack is provided between the inner edge of the shutter and the screen 21 through which an indirect and consequently mellow light will be admitted to the 80 table 31 adjacent the inner side of the blade 23 for furnishing sufficient illumination to the table to permit accurate trimming of the print.

To overcome the possibility of trimming a photographic print too close or actually cutting the picture, the reflector 18 is provided. Indirect rays from the lamp 40 will be cut off from the reflector by the screen 21 so that the said reflector will direct a strong 90 light through the window 36 and against the outer side of the cutting blade 23 at the shearing edge thereof. Consequently, the margin of a picture when projected over the blade 23 into the light from the reflector 95 will be rendered translucent so that the edge of the picture may be readily perceived and accurately positioned with respect to the shearing edge of the said blade. It has been found that this feature of the present invention constitutes a highly advantageous arrangement and one tending to materially expedite the operation of trimming photographic prints. Shavings from the prints will fall upon the shavings board 19 to be 100 directed thereby over the reflector 18 to a position out of the way.

It will therefore be seen that this invention will alleviate the present inaccurate and tedious methods of trimming photographic prints in that a means is provided for quickly positioning the print ready for trimming with the future margin visible before it is cut.

Having thus described the invention, what 115 is claimed as new is:

1. A device of the character described including a body providing a lamp chamber, a transparent cutting table arranged at the upper side of the body, cutting means carried by the body at one extremity thereof, and a shutter carried by the body for cutting off a portion of the light rays from a lamp within the said chamber at a point adjacent the inner side of the said cutting 120 means.

2. A device of the character described including a body providing a lamp chamber, a cutting table arranged at the upper side of the body, cutting means carried by the body 125

- adjacent one extremity thereof, and a reflector carried by the body in advance of the said cutting means for directing the rays from a lamp within the said chamber against 5 the outer side of the said means. 70
3. A device of the character described including a body providing a lamp chamber, a transparent cutting table arranged at the upper side of the body, cutting means carried by the body adjacent one extremity thereof, a reflector arranged within the body below the said table, and a second reflector mounted in advance of the said cutting means, the said reflectors being respectively 10 75 adapted to direct the rays from a lamp within the said chamber toward the cutting table and against the outer side of the said cutting means.
4. A device of the character described including a body having side walls joined by a top wall, the top wall being free for a portion of its length and being inclined between the side walls to provide a reflector within the body and thence extended to 15 80 form a second reflector, a transparent cutting table arranged at the upper side of the body, and cutting means carried by the body adjacent one extremity thereof, the said reflectors being adapted to direct the rays 20 from a lamp arranged therebetween up through the said cutting table and against the outer side of the said cutting means. 85
5. A device of the character described including a body provided with a lamp chamber, a transparent cutting table arranged at the upper side of the said chamber, cutting means carried by the body, and a shavings board sloping forwardly and downwardly from the said cutting means. 90
6. A device of the character described including a body, a cutting table arranged at the upper side of the body, cutting means carried by the body, a reflector arranged in advance of the said cutting means, and a shavings board sloping downwardly from the said cutting means over the said reflector and provided with a window opening, the said reflector being adapted to direct the light rays from a lamp within the body 45 95 through the said window opening against the outer side of the said cutting means. 100
7. A device of the character described including a body, a cutting table arranged at the upper side of the body, cutting means carried by the body, a reflector arranged in advance of the cutting means, and a screen projecting into the body and arranged to cut off above the reflector indirect light rays from a lamp arranged within the body, the 50 105 said reflector being adapted to direct the light rays against the outer side of the said cutting means.
8. A device of the character described including a body having side walls joined by a top wall, the top wall being freed from 55 110 the side walls and extended therebetween to provide a lamp chamber, a transparent cutting table arranged at the upper side of the said chamber, and cutting means carried by the body. 115
9. In a trimmer for photographic prints, the combination of a body, a transparent cutting table arranged at the upper side of the body, cutting means carried by the body, and reflectors within the body for illuminating a print upon the said table at opposite sides of said cutting means. 120
10. A device of the character described including a body providing a lamp chamber, cutting means carried by the body adjacent one extremity thereof, and means for directing the rays from a lamp within the said chamber toward the outer side of the said cutting means. 125
11. A device of the character described including a body providing a lamp chamber, cutting means carried by the body adjacent one extremity thereof, and means carried by the body in advance of the said cutting means for directing the rays from a lamp within the said chamber toward the outer side of the said cutting means. 130
12. A device of the character described including a body providing a lamp chamber, cutting means carried by the body, and means carried by the body for directing the rays within the said chamber toward opposite sides of said cutting means. 135
13. A device of the character described including a body providing a lamp chamber, and cutting means carried by the body adjacent one extremity thereof, a wall of the body being arranged to provide a reflector for directing the rays from a lamp within the said chamber toward the outer side of 140 145 said cutting means. 150
14. A device of the character described including a body providing a lamp chamber, a transparent cutting table carried by the body, cutting means carried by the body adjacent one extremity thereof, and means for cutting off a portion of the rays from a lamp within the said chamber at one side of the said cutting means. 155
15. A device of the character described including a body providing a lamp chamber, a transparent cutting table carried by the body, cutting means carried by the body adjacent one extremity thereof, means for directing the rays from a lamp within the 160 165 said chamber against the outer side of said cutting means, and means for cutting off indirect light rays above the said first mentioned means. 170
16. A device of the character described including a body having side walls provided with flanges, a wall extending between said side walls and resting upon said flanges to form a lamp chamber within the body, the said wall being curved to provide a reflector, 175 180

and cutting means carried by the body adjacent one extremity thereof, the said reflector being arranged to direct the rays of a lamp within the said chamber toward the outer side of the said cutting means.

17. A device of the character described including a body providing a lamp chamber, a transparent cutting table carried by the body, cutting means carried by the body

adjacent one extremity thereof, a reflector 10 mounted to direct the rays of a lamp within the said chamber toward the outer side of the said cutting means, and means for cutting off indirect light rays from the lamp above the said reflector and from the reflector at 15 the inner side of the said cutting means.

In testimony whereof I affix my signature.

ROBERT M. CATHCART.
